UNITED STATES PATENT OFFICE.

CARL F. GERLINGER, OF DALLAS, OREGON.

LUMBER CARRIER.

1,422,958.

Specification of Letters Patent.

Patented July 18, 1922.

Application filed August 30, 1921. Serial No. 496,799.

To all whom it may concern:

Be it known that I, CARL F. GERLINGER, a citizen of the United States, residing in Dallas, in the county of Polk and State of Oregon, have invented certain new and useful Improvements in Lumber Carriers, of which the following is a specification.

This invention relates to lumber carriers of the kind in which provision is made for raising a load of lumber, for carrying it to its destination, and for depositing it there.

While my improvements are especially intended for the purposes already mentioned they may be embodied in trucks or carriers for raising and conveying loads of various kinds, but as my improvements are especially intended for carrying lumber they will, for the most part, hereafter be referred to for that purpose.

According to this invention, I provide a wheeled frame or truck, equipped with means for driving and steering it, and with means for causing lifting devices to engage the load and raise it so that it can be properly transported. The driving mechanism is such that the truck may be driven either forwards or backwards, and automatic devices are employed for stopping the elevating mechanism and for releasing the load when desired. Automatic devices are also employed for stopping the descent of the elevating devices when lowered.

Instead of employing ropes or cables for operating the lifting shoes I employ shafts and gearing of substantial and reliable construction and which are controlled by clutch mechanism, in turn controlled by suitable levers.

In the accompanying drawings:—

Figure 1 shows a side elevation of a lumber carrier embodying my improvements, certain parts being shown in section to illustrate details of construction.

Figure 2 is a plan view of my improved lumber carrier.

Figure 3 is a front elevation of the same.

Figure 4 is a side elevation of a portion of the rear end of the truck.

Figure 5 is a rear elevation of the lumber carrier.

Figure 6 is a detail view, showing the construction and mounting of one of the lifting shoes when in lifting position.

Figure 7 is a similar view, showing the shoe withdrawn or removed from lifting position.

The main frame of the truck or carrier comprises a platform A having front arms or brackets a and rear arms or brackets a' which project laterally sideways from the truck. At the front of the truck there are vertical frame parts a^2 preferably made of channel iron which extend downwardly from the platform and at the rear of the truck there are similar vertical frame parts a^3 . The frame parts a^2 , a^3 are braced by brace bars a^4 , a^5 and a^6 , as shown in Fig. 1. It will be observed by reference to Fig. 3 that the frame as a whole is of a general U shape so that it may be drawn over a load supported by a table or carrier X.

The front wheels B, which are the steering wheels, are journaled in U-shaped frames C, carrying posts D, supported in suitable brackets E and having collars d supporting springs F on which the frame arms a of the platform rest. The upper ends of the posts D carry crank arms G connected by a link G'. One of the posts D has an arm g which is connected by links g' , g^2 with the steering mechanism H. It is obvious from an inspection of Fig. 1 that by operating the wheel H the truck may be conveniently steered.

The rear wheels J are journaled in U-shaped frames j, carrying posts J' extending through brackets j' and having collars k supporting springs K on which rest the rear arms a' of the platform.

The rear wheels carry bevel gears l with which mesh bevel pinions l' on shafts L having universal joints at l^2 and an extensible connection at l^3 .

Each shaft L, as shown, is made in two parts, the part 1 which carries the pinion l' and enters a sleeve l^3 , the part 3 which also enters the sleeve l^3 and is joined at l^2 to the part 4 which latter part carries at its upper end a pinion l^4 . The several parts of the shafts L are supported and guided by the frame parts a^3 . By this construction provision is made for allowing the truck to traverse rough ground without strain upon the gearing.

The pinions l^4 of the shafts L gear with pinions M on a shaft N extending crosswise of the truck above the platform, and mounted to turn in suitable bearings thereon. The shaft N carries spur wheels O, O' adapted to engage similar wheels P, P', on the shaft Q, carrying a beveled pinion R adapted to engage either of the cone gears r , r' on the shaft S driven by the engine T. The gear

wheels O, O', P, P' are change gears constructed and operated in the usual way and need not be further described. The shaft N carries brake mechanism N' which may also 5 be of ordinary construction and need not be further described.

The cone gears r , r' are associated with clutches r^2 , r^3 . These clutches are of well known construction, being of the cone type, 10 and are for the purpose of connecting either one of the pinions r , r' with the driving shaft S so that the shaft N may be driven in either direction to propel the truck forward or backwards. The clutches are operated and controlled by a lever T' which 15 operates levers t , t' connected by a link t^2 . The lever T' has detent mechanism operating in a toothed segment t^3 . The lever may be set to hold the clutch mechanism in neutral 20 position so that there is no driving connection between the shaft S and the shaft N, or it may be operated when pushed forward to connect the shaft S with the shaft N to advance the vehicle. When the lever 25 T' is pushed backwards to its full extent, the connections are proper for driving the truck backwards.

The shaft S carries at its rear end cone gears v , v' which engage bevel gears u , u , 30 on shafts U, U'. These shafts U, U' are parts of mechanism for operating the load-lifting devices.

The gears v , v' are associated with cone clutches V, V' on the shaft S and these 35 clutches are associated with shifting devices whereby the shafts U, U' may be driven in either direction. As shown, the appropriate clutch mechanism is engaged by levers w , w' connected by a link w^2 . The lever w' is 40 attached to a horizontal rod w^3 to which the operating lever W is secured. The lever W is provided with a detent engaging a segment W' having a single notch as shown. When the detent engages the notch the lever 45 is in a neutral position, and then the shafts U, U' are not operatively connected with the shaft S. The lever w is pivoted at w^4 . The rod w^3 carries arms w^5 which extend downwardly and rearwardly in the truck frame 50 and are connected at their lower ends by a rod w^6 . When the arms w^5 are swung upwards or downwards they operate the clutch mechanism in the manner shown. The shaft w^4 carries an arm w^7 which is operated by 55 devices hereinafter described to automatically operate the clutch mechanism at certain times.

The lifting mechanism comprises the shoes Y suspended from rack bars Y' by links y , y' . The links are pivotally connected at y^2 , y^3 to the rack bars and pivotally connected at y^4 , y^5 to the shoes. It will be understood 60 that there are four lifting shoes, one on each side of the front of the truck and one on each side of the truck at the rear. A spring 65

y^6 connects each link y' with its companion link y at its pivot, and a spring y^7 connects each link y between its ends with the adjacent shoe at the pivot point y^5 of the link y' . The construction is such that the shoes 70 always lie in horizontal plane whether under the load or withdrawn therefrom.

The rack bars Y' are guided in the frame parts a^2 and a^3 and they are provided at their upper end with teeth z engaged by spur 75 wheels z' on shafts Z mounted in suitable bearings on the platform A. The shafts Z carry worm wheels Z^2 which engage worms Z^3 on the shafts U, U'. By this mechanism, when the shafts U, U' are operatively connected with the shafts S, the rack bars may be raised and lowered, the direction of movement being controlled by the clutch mechanism. By operating the lever 80 W the lowering devices may be raised or lowered as desired. When being raised or lowered the lever is held by the operator. When the shafts U, U' are disconnected from the shaft S the detent may be made to engage the segment W' to hold the mechanism in neutral position. 85

The arm w^7 of the rod w^4 is adapted to be engaged by a lug w^8 on one of the rack bars. When the rack bars are lowered to the full extent, or the desired extent, the lug thus 90 engages the arm w^7 and operates the clutch mechanism to disconnect the shafts U, U' from the operating shaft.

It will be observed by reference to Figs. 6 and 7, that when the shoes Y are being 100 raised and lowered they are guided in the frame parts a^2 , a^3 . By reference to Fig. 7 it will be observed that when the shoes are lowered to their full extent they are withdrawn towards the sides of the truck so as to leave a clear space for the truck to pass over a load and get into position to lift the load. The shoes are held in the position shown in Fig. 7 by the springs y^6 , y^7 , the links y being held against the frame parts 105 a^2 , a^3 . When the rack bars are operated to raise the shoes, in the manner shown in Fig. 6, the springs yield and the links y , y' assume a vertical position, as shown. At this time the shoes are under the load, as indicated in Fig. 5, and the load with its support X is clear of the ground. The truck 110 may then be propelled to carry the load to its destination. 115

When the load has reached its destination, 120 the lever W may be operated to so clutch the shafts U, U' to the shaft S that the rack bars will be lowered to deposit the load. In order that shocks may be avoided, the lug w^8 is provided to engage the clutch mechanism 125 and disconnect it so that the lowering operation may be suspended at the proper time.

In like manner, when the shoes are being raised the clutch mechanism may be disconnected by the devices before described to 130

suspend the raising operation. This is brought about by the top of the load coming in contact with the rod w^6 and swinging the same with the arms w^5 . This rocks the shaft 5 or rod w^3 and through the lever w' moves the clutch to disconnect the lifting mechanism from the operating shaft.

It will thus be seen that means is provided whereby an engine or motor on the truck may 10 propel it either forwards or backwards and this same engine may be employed to operate the lifting mechanism to either lift or lower the load. The connections between the engine and the other mechanisms are positive, being composed mainly of shafts and 15 gears, no cables or ropes being used. Experience has demonstrated that the automatic devices for stopping the lifting and lowering mechanism are of great practical 20 importance and the mechanism whereby the clutches may be controlled manually as well as automatically are also useful in service.

I claim as my invention:

1. A lumber carrier or truck comprising 25 a frame, front and rear wheels on which the frame is supported, lifting shoes, vertically movable rack bars, connecting links directly pivoted to the shoes and to the rack bars, an engine on the frame, and connections between the engine and the rack bars for 30 raising and lowering the shoes.

2. A lumber carrier or truck comprising a frame, an engine on the frame, lifting shoes, vertically movable rack bars, connecting links directly pivoted to the shoes and to the rack bars, springs associated 35 with the shoes and links tending to move the shoes outwardly sidewise, and connections between the engine and the rack bars whereby the shoes may be raised and lowered.

3. A lumber carrier or truck comprising an engine, a platform, vertical frame members depending therefrom, vertically movable rack bars guided in said frame members, 45 links pivotally connected to said rack bars, lifting shoes pivotally connected to said links and extending horizontally in both raised and lowered positions, springs engaging said links for moving the shoes outwardly sidewise when the rack bars are lowered, and connections between the engine and the rack bars whereby the lifting shoes 50 may be raised and lowered.

4. A lumber carrier or truck comprising 55 a wheel-supported frame, an engine on the frame, connections between the engine and the wheels whereby the truck may be propelled, lifting shoes, vertically movable rack bars with which they are connected, opera-

tive connections between the rack bars and 60 the engine for both raising and lowering the shoes, and automatic devices for disconnecting the rack bars from the engine when the shoes have been raised to a predetermined extent.

5. A lumber carrier or truck comprising a wheel-supported frame, an engine on the frame, connections between the engine and the wheels whereby the truck may be propelled, lifting shoes, vertically movable rack 70 bars with which they are connected, operative connections between the rack bars and the engine for both raising and lowering the shoes, and automatic devices for disconnecting the rack bars from the engine when the 75 shoes have been lowered to a predetermined extent.

6. A lumber carrier or truck comprising a frame, an engine supported thereby, a shaft driven by the engine, lifting shoes, vertically 80 movable rack bars with which they are connected, gearing connecting the rack bars with the shaft driven by the engine, manually operated means for shifting the gearing to either raise or lower the rack bars, and 85 devices for automatically shifting the gearing to arrest the upward movement of the rack bars when the shoes have been raised to a predetermined position.

7. A lumber carrier or truck comprising a 90 frame, an engine supported thereby, a shaft driven by the engine, lifting shoes, vertically movable rack bars with which they are connected, gearing connecting the rack bars with the shaft driven by the engine, manually operated means for shifting the gearing to either raise or lower the rack bars, and 95 devices for automatically shifting the gearing to arrest the downward movement of the rack bars when the shoes have been lowered to a predetermined position.

8. A lumber carrier or truck comprising a wheel-supported platform, an engine supported on the platform, vertically arranged side frame members, vertically movable rack 105 bars guided in said members, operative connection between the rack bars and the engine, lifting shoes, links pivotally connected with the rack bars and with the shoes, springs operating on the links to move the 110 shoes sidewise outwardly when the rack bars have been lowered to a predetermined extent but which yield and permit the shoes to move inwardly to engage the load when the rack bars have been sufficiently raised.

In testimony whereof, I have hereunto subscribed my name.

CARL F. GERLINGER.
